UNITED STATES PATENT OFFICE.

JOHN W. KERR, OF LOS ANGELES, CALIFORNIA.

CAN CAP AND SEAL.

1,343,782.

Specification of Letters Patent. Patented June 15, 1920.

Application filed November 12, 1919. Serial No. 337,532.

To all whom it may concern:

Be it known that I, JOHN W. KERR, a citizen of the United States, residing at Los Angeles, in the county of Los Angeles and 5 State of California, have invented new and useful Improvements in Can Caps and Seals, of which the following is a specification.

This invention relates to a can cap and seal adapted to be applied to containers for 10 liquids.

Evaporated milk and liquids are commonly conserved in tin cans. It is common practice to serve the liquid by puncturing the lid of the can at diametrically opposite 15 points, one puncture serving for egress of the liquid and the other for the ingress of air. Thus, the liquid may be readily poured from the can. Another object in puncturing the lid is to provide openings which are 20 automatically sealed by the film of liquid spreading across the openings and then drying, thereby closing the same. As it is seldom that the full contents of the cans are used at one time, this is very advantageous. 25 If the openings are too large, a film will not form across the former, and the can remains unsealed. When sealed by the film, it is necessary to puncture the dry film to open the can. Furthermore, some sharp instrument 30 must be used to originally puncture the can. The lid becomes dirty and is unsanitary.

It is the primary object of my invention to provide a cap to cover the can having 35 means by which two large punctures may be made simultaneously, said cap being provided with valves and means to expeditiously open and seal the same at will. It is another object of this invention to provide a cap of 40 the character described with puncture tubes which serve as conduits for the liquid.

These objects will be more fully understood as will also other objects and corresponding accomplishments of my invention 45 from the following detailed description of a preferred embodiment thereof. For the purpose of this description, reference is had to the accompanying drawing, in which:

Figure 1 is a vertical section through the 50 upper part of a can and my improved cap and seal; Fig. 2 is a section through the cap and seal taken on the line 2-2 of Fig. 1; and Fig. 3 is an elevation of the cap applied to a can.

55 Referring more particularly to the draw-

ing, A indicates a can and B is the cap applied thereto. The cap is portable and may be removed from a can and applied to another can.

Referring particularly to the cap, it has 60 a base 4 upon which is mounted a dome 5. The base 4 is of the size of the lids of cans to which it is intended to be applied, and is adapted to be disposed thereover as shown in Fig. 1. The base and dome are conveniently made of any suitable metal. Extending through the dome and base at diametrically opposite points are puncture tubes 6 and 7. The bottoms of the tubes extend beyond the base and are beveled to 70 form points for puncturing the lid. The top of the tubes are elevated above the top of the dome serving as conduits for air and liquid with the upper ends as seats for valves. Secured to the dome intermediate 75 the tubes are standards 8 and 9, upon which are pivoted arms 10 and 11 respectively. The outer ends of the arms are so constructed as to provide valve disks 12 and 13 for seating upon the ends of the puncture 80 tubes. Packing 14 and 15 of rubber or any suitable resilient material which will seal the ends of the tubes is secured to the valve disks. Formed on the inner end of arm 11 are inturned lateral flanges 16 and 17 forming a head 18 in which rides a pin 19 secured to arm 10.

This provides for simultaneous operation of the valves. In order to maintain the valve in closed position, a compression spring 20 90 is disposed between the dome and the head 18. In order to maintain a tight fit at the puncture tubes, washers 21 and 22 of resilient material are disposed over the tubes 6 and 7 and in contact with the base 4 so 95 as to seat over the holes formed in the lid and seal the same.

The cap is used in the following manner: When it is desired to open a can, the cap is placed over the lid with the penetrating 100 ends of the puncture tubes in position to puncture the lid. The cap is then pressed downwardly so that the tubes puncture the lid and extend into the can. Pressure is continued until the washers 21 and 22 rest 105 upon the top or lid of the can. The cap is now ready for use in pouring.

To pour liquid from the can, the latter is tilted with one of the puncture tubes on the lower side and the other on the upper. 110

The head 18 is then depressed by the finger of the operator, thereby lifting valve disks 12 and 13 from the tubes and opening the latter. Liquid will then flow from the lower 5 puncture tube and air will enter the upper tube passing to the can and filling the space vacated by the liquid which flows from the can.

What I claim is:

- 10 1. A device of the class described comprising a cap adapted to be disposed over the lid of a can, puncture tubes therein at diametrically opposite points, rock arms having valves at the ends thereof to close 15 said tubes, means tending to hold said rock arms with the valves in closed position, said arms being provided with means for simul-

taneously rocking the latter to open said valves.

2. A device of the class described comprising a cap adapted to be disposed over the lid of a can, puncture tubes therein at diametrically opposite points, rock arms having valve disks at the ends thereof to seat on the ends of the tubes, means tending to hold said rock arms with the valves in closed position, said arms being provided with means for simultaneously rocking the latter to lift said disks and open said tubes. 25

In witness that I claim the foregoing I 30 have hereunto subscribed my name this 5th day of November, 1919.

JOHN W. KERR.
